ANTIOXIDANTS AND METHOD OF
PRODUCING SAMELoran O. Buxton, Newark, N. J., assignor to
Nepco Chemical Company, Harrison, N. J., a
corporation of New JerseyNo Drawing. Application November 19, 1943,
Serial No. 510,974

18 Claims. (Cl. 252—398)

1

This invention relates to novel antioxidants derived from the "soap stock" or "foots" produced incidentally to the alkali refinement of vegetable oils, and to a method of producing these antioxidants.

Antioxidants have hitherto been derived from a wide variety of source materials and used as preservatives in a large number of oxidation-sensitive organic substances such as vitamin preparations, foodstuffs, oils, fats, lubricants, fuels, rubber compositions, etc. However, antioxidants are not of equal effectiveness in all substances, the action of any particular antioxidant in admixture with any particular oxidation-sensitive substance being peculiar to that particular combination of antioxidant and substance. Further, the source materials heretofore employed for the production of antioxidants are not always of low cost or ready availability. Accordingly, there exists a wide field for the introduction of novel antioxidants and for the discovery of new source materials therefor.

In the usual process of refining vegetable oils, the crude oils are preliminarily treated by means of alkali, followed by a separation of the resultant soap complex from the oil. The separated soap complex material is variously known as "foots," "soap stock" and the like. Hereinafter, such materials will be designated "soap stocks." It has not heretofore been realized that soap stocks contain substantial quantities of antioxidants or that they could be used as source materials for the production of antioxidants.

Accordingly, it is an object of this invention to provide novel antioxidants.

Another object is to provide antioxidants which will have a more effective action than antioxidants heretofore produced.

Another object is to employ, as source materials for antioxidants, the relatively plentiful and cheap soap stocks obtained in the alkali refinement of vegetable oils.

The foregoing and other objects are secured in accordance with this invention in a process which involves the extraction by means of non-polar solvents at relatively high temperatures of soap stocks obtained in the alkali refinement of vegetable oils. The solvent extract is separated from the soap stock, and the solvent removed from the extract, leaving a product which exerts a very effective antioxidant action when compounded with a wide variety of oxidation-susceptible pharmaceutical, food and industrial materials. The antioxidant extracts of this invention exert a particularly effective action when used in conjunction with phosphatides, such as the lecithins, with which they appear to exert a synergistic effect far in excess of the antioxidant power of either the antioxidant itself or the phosphatides.

The solvents employed in the extraction step

2

of this invention may be any relatively low molecular weight, non-polar, water-immiscible, organic solvents which will not dissolve any appreciable quantity of the soaps in the soap stock complex to be treated. Such solvents are exemplified in hydrocarbon solvents such as hexane, heptane, cyclohexane, methyl cyclohexane, petroleum ether, naphtha and the like; or chlorinated hydrocarbon solvents such as ethylene dichloride, trichlorethane, chloroform, carbon tetrachloride and the like. Mixtures of solvents above indicated as suitable may likewise be employed.

Soap stocks suitable as source materials in the process of this invention may be any soap stocks conventionally produced in the alkali refinement of vegetable oils such as corn oil, peanut oil, linseed oil, coconut oil, soyabean oil, cottonseed oil, sesame oil or the like. Instead of relying upon commercially produced soap stocks as source materials for the antioxidants of this invention, it would likewise be advantageous to carry out an alkali refinement of a vegetable oil with a special view to providing a soap stock more suitable for use as a source material in this invention; for instance, the alkali treatment could be carried out in an inert atmosphere, or in the presence of reducing agents such as sodium sulfite, morpholine sulfite, and the like. In this case, in addition to the corn, etc. oils above named as being conventionally alkali refined, other oils providing special antioxidant products might be employed, such as corn germ oil, wheat germ oil, rice germ oil, fish liver oils, cranberry seed oil, and the like. In any case, the soap stock should be extracted in accordance with the invention as soon as possible after its production from the oil, and/or should be stored at low temperatures during the interval between production and utilization in this invention, since the soap stock at ordinary temperatures tends to deteriorate by fermentation, hydrolysis of the soaps, and destruction of the antioxidant principles therein.

Alkali refinement of vegetable oils is highly conventional and need not be further discussed herein beyond pointing out the principal types of such refinement, viz. (a) processes in which the crude oil is contacted with caustic alkali, such as caustic soda or potash; (b) processes in which the crude oil is washed with aqueous soda ash solution; and (c) processes in which the crude oil is first treated with a primary wash of aqueous soda ash solution followed by treatment with caustic alkali. The commercial processes may, of course, be slightly varied with a special view to producing more suitable source materials for the practice of this invention, for instance, a more dilute caustic may be employed, the reaction may be carried out in an inert atmosphere, potash caustics could be used in place of the soda

caustics ordinarily used, etc. In all of the above processes, the fatty acids and easily saponifiable matter in the crude oil are converted to soaps, which entrain various other materials such as sterols, "break" constituents and the like and are separated from the oil by gravity settling or centrifugation. The resultant separated soap and entrained matter form the source materials for the preparation of antioxidants according to this invention. Of the various types of soap stocks, those prepared by the simple contact of caustic soda in accordance with (a) above are the preferred source materials for the practice of this invention: however, soap stocks prepared by the other methods are entirely suitable.

At present, the soap stocks prepared as above outlined are usually marketed in the form of acids prepared by splitting the original soap stocks. For use in this invention, such acidulated soap stocks must be reconverted to the alkali soaps by treatment with alkali, either sodium or potassium. Accordingly, it is preferred to utilize the original soap stocks as separated from the refined oils, so as to avoid the unnecessary manipulations of acidulation and reconversion to soap.

The extractions according to this invention are conducted by contacting the soap stock with from about $\frac{1}{2}$ to about 3 times its weight of any non-polar solvent above indicated as suitable, at temperatures varying upwards of about 40° C. in cases where sodium soap stocks are treated, and 30° C. in cases where potassium soap stocks are treated, to the boiling point of the solvent under the conditions of the extraction. In cases where ethylene dichloride is used, the boiling point will be between 80 and 90° C. In general, it will be preferred to operate between 60° and 70° C. The solvent and soap stock are thoroughly agitated together to insure contact of the solvent and soap stock. The solvent and matter dissolved thereby will ordinarily spontaneously separate from the soap stock by gravity upon cessation of agitation, and may be removed mechanically. However, if necessary, or preferred, centrifugation may be employed. Ordinarily, a single extraction conducted in this manner will not remove all of the valuable antioxidant principles from the soap stock, which retains these principles with considerable tenacity. Accordingly, the usual procedure will be to repeatedly extract the residual soap stock with fresh lots of non-polar solvent. The several extract solutions may either be combined for further working up, or may be worked up separately. The solvent is removed from the combined extracts or several individual extracts, as the case may be, leaving an extract residue which constitutes the antioxidant product of this invention.

The residual soap stocks left behind by the extractions conducted according to this invention may be worked up in the usual ways in which ordinary soap stocks are treated, as by acidification, distillation, etc. For many of these purposes, the soap stocks will be greatly improved by having been subjected to the extraction of this invention.

The antioxidant product produced as just outlined may be further refined, concentrated, etc. by any appropriate means such as fractionation with solvents, high vacuum distillation, etc.

While the composition of the antioxidant products of this invention is somewhat obscure, and moreover varies in accordance with the original vegetable oil and subsequent conditions of processing, it may be stated in a general way

that the products contain, as active antioxidant components, various chromanes, quinones, quinols, tocopherols (as vitamin E) and similar compounds. In addition, the products also contain sterols, provitamin A, neutral oil and other undetermined substances.

The antioxidant extracts of this invention may be used to stabilize a wide variety of oxidation-susceptible pharmaceutical, alimentary and industrial products such as fat-soluble vitamin preparations on the order of vitamin A-, D- and E-containing oils, concentrates and the like; in foodstuffs, such as butter, margarine, fried products (such as potato chips), breakfast foods, salad oils, and the like; in cosmetic preparations, such as creams, lotions, etc.; and in industrial compositions such as lubricants, fuels and rubber compositions. The amount of antioxidant necessary to employ in any case will vary in accordance with the particular material to be stabilized, the source of the soap stock from which the antioxidant is produced, and the degree of antioxidant protection required. Accordingly, this amount is best determined by experiment in each case. In general, between about 0.5% and about 7% of antioxidant based on the weight of material to be stabilized will provide a highly satisfactory degree of antioxidative stabilization.

The antioxidants of this invention exert a particularly effective action when used in combination with phosphatides on the order of lecithin, soyabean lecithin and the like, which latter, although they themselves exert no substantial antioxidant action, nevertheless seem to greatly enhance the effectiveness of the antioxidants of this invention. Based upon the use of a single part, by weight, of the antioxidants of this invention, it will be found highly advantageous to employ in conjunction therewith from about $\frac{1}{16}$ to about 1 part of phosphatide. More of the phosphatide may be employed, but will not greatly enhance the effectiveness of the applicant's antioxidants.

With the foregoing general discussion in mind, there are given herewith concrete detailed examples of the practice of this invention. All parts given are by weight.

EXAMPLE I

Antioxidants from cottonseed soap stock

Cottonseed oil soap stock _____ parts _____ 57
 Ethylene dichloride _____ six 114-part portions

The cottonseed soap stock and first portion of the ethylene dichloride were mixed and heated to 70° C. in a kettle containing a nitrogen atmosphere. The mixture was stirred vigorously at this temperature for 30 minutes and then allowed to settle into a lower layer containing the ethylene dichloride and materials extracted thereby, and an upper soap layer. The ethylene dichloride layer was drawn off and the soap layer extracted with the second portion of ethylene dichloride in the same manner. The soap stock was repeatedly extracted in the same manner with the remaining portions of ethylene dichloride, making a total of 6 extracts. These extracts were combined and chilled to +3° C. and filtered. The clear filtrate was subjected to vacuum distillation to remove the ethylene dichloride, leaving a residue of 2.54 parts of a dark brown semi-solid product. This product, hereinafter designated "A," was found to stabilize a wide variety of oxidation-sensitive materials against oxidative

deterioration. This material contained 25% unsaponifiable matter, as compared to less than 2% for crude cottonseed oil. Quantitative data on accelerated tests of a vitamin A-containing oil stabilized with antioxidant "A" are presented in the table hereinbelow after Example XV.

EXAMPLE II

Acetone fractionation of product "A"

Antioxidant product "A" of Example I 10 Parts 200
Acetone: 200

1st portion 800
2d portion 400

Product "A" and the first portion of the acetone were mixed and slightly warmed to effect a clear solution. This solution was then cooled to +3° C. and kept at this temperature for five days. The mixture was filtered, producing a crystalline residue "B," which was washed with small portions of acetone at +3° C., and a filtrate "C," the latter which included the washings just mentioned. The residue "B" was dissolved with heating in the second portion of acetone, the solution cooled to +3° C., and held at this temperature for 18 hours. The resultant mixture was filtered producing a residue which was washed with small portions of acetone at +3° C., and a filtrate "D" which included the washings last mentioned. Filtrates "C" and "D" were combined, and the acetone evaporated off until the solution comprised about 500 parts. This solution was kept at -10° C. for 18 days, filtered, and the residue washed with small portions of cold acetone. The filtrate and washings were combined and the solvent evaporated off therefrom, leaving 101 parts of a product "E" having a high antioxidant potency. Results of tests conducted on this material are tabulated after Example XV.

EXAMPLE III

Antioxidants from soyabean oil soap stock

The procedure of Example I was precisely repeated using a soyabean oil soap stock in place of the cottonseed oil stock as a starting material. Corresponding to product "A," there were obtained 1.74 parts of an orange-red solid product "F" having effective antioxidant properties. This product contained 50% unsaponifiable matter as compared to less than 2% for crude soyabean oil. Quantitative data on accelerated tests of a vitamin A-containing oil stabilized with antioxidant "F" are represented hereinbelow after Example XV.

EXAMPLE IV

Acetone fractionation of product "F"

Antioxidant "F" of Example III 163 Parts
Acetone: 163

1st portion 750
2d portion 400

The procedure of Example II was precisely repeated using the materials above listed in place of the corresponding materials of Example II. There were obtained 71 parts of a semi-solid product "G," which exhibited effective antioxidant properties.

EXAMPLE V

Antioxidants from corn oil soap stock

The procedure of Example I was precisely repeated, using a corn oil soap stock in place of the cotton seed oil soap stock of Example I.

There were obtained 3.4 parts of a highly efficient antioxidant product "H," corresponding to the product "A" of Example I. Product "H" was found to be a highly effective antioxidant in combination with a wide variety of oxidation labile materials. This product contained 41% of unsaponifiable material, as compared to less than 2% for crude corn oil. Quantitative data obtained by tests of this material in admixture with a vitamin A-containing oil are presented herein-after in the table following Example XV.

EXAMPLE VI

Acetone fractionation of product "H"

Antioxidant Product "H" of Example V 70 Parts
Acetone: 70

1st portion 300
2d portion 400

The procedure of Example II was precisely repeated using the materials above listed in place of the corresponding materials employed in Example II. There were obtained 44 parts of a brilliantly clear liquid antioxidant product "J" corresponding to the product "E" of Example II.

EXAMPLE VII

Antioxidant from soyabean oil soap stock

Soyabean oil soap stock 100 Parts
Trichloroethane: 100

1st portion 200
2d portion 200
3d portion 200

The soap stock and first portion of trichloroethane were mixed and agitated together at 70° C. The soap stock dissolved to a considerable extent at this temperature and, accordingly, the mass was cooled at 43° C. and permitted to separate into an upper soap stock layer and a lower trichloroethane extract solution layer, which latter was drawn off. The residual soap stock was successively extracted with the other portions of

trichloroethane by the same procedure. The several extracts were combined, chilled to +3° C. and retained at this temperature for 18 hours. Thereafter, the solution was filtered, and the filtrate subjected to vacuum distillation to remove trichloroethane, yielding 18.3 parts of a dark orange-red antioxidant product "K."

EXAMPLE VIII

Antioxidant from soda ash corn oil soap stock

Soda ash corn oil soap stock parts 200
Ethylene dichloride five 400-part portions

The soap stock and the first portion of ethylene dichloride were mixed and agitated together at 60° C. to effect thorough contact therebetween, after which agitation was discontinued and a layer of ethylene dichloride (containing the material extracted thereby from the soap stock) was allowed to separate and was removed. The residual soap stock was again and again reextracted in the same manner successively with the other portions of ethylene dichloride. The several extract solutions were combined, chilled to +3° C. and allowed to stand for 18 hours. Thereafter, the extracts were filtered and the filtrate subjected to distillation to yield 21 parts of a red viscous liquid antioxidant product L, containing 7.7% of unsaponifiable material. Tests on this product are recorded in the table following Example XV.

EXAMPLE IX

Antioxidants from soda ash cottonseed oil soap stock

The procedure of Example VIII was precisely repeated using a soda ash cottonseed oil soap stock in place of the corn oil soap stock of Example VIII. There were obtained 20 parts of a dark red clear viscous liquid antioxidant product "M" having an iodine value of 100, a saponification value of 187, and containing 8% of unsaponifiable material. Test data on this product are recorded in the table following Example XV.

EXAMPLE X

Antioxidant from expeller soyabean oil soap stock

Expeller soyabean oil soap stock parts 500
Ethylene dichloride:

1st portion do 2000 20
Additional portion seven 1000-part portions

The soap stock and the first portion of ethylene dichloride were mixed and agitated together at 70° C. until thorough contact had been effected. Thereafter, the agitation was discontinued and the ethylene dichloride extract layer was permitted to settle and was removed. The residual soap stock was repeatedly reextracted with the remaining portions of ethylene dichloride in the same manner. All of the extracts were combined, cooled to +3° C. and held at this temperature for 18 hours. Thereafter, the extracts were filtered, and the filtrate subjected to vacuum distillation to remove the ethylene dichloride, leaving behind 30 parts of a clear dark red viscous liquid antioxidant product "N" having an iodine value of 162 and containing 18% unsaponifiable material. Tests on this product are tabulated hereinbelow.

EXAMPLE XI

The procedure of the preceding example was precisely repeated, using a soap stock produced from hydraulic cottonseed oil and separated from the refined oil by centrifugation. There were obtained 22 parts of a clear dark red solid antioxidant product "O" (corresponding to product "N") having an iodine value of 106 and containing 31% unsaponifiable material. See the table hereinbelow for test data on this product.

EXAMPLE XII

Antioxidant from expeller cottonseed oil soap stock

The procedure of Example IX was precisely repeated using a soap stock obtained from an expeller cottonseed oil. There were obtained 12 parts of a solid black-red antioxidant product P. See the table for test data.

EXAMPLE XIII

Antioxidant from acidulated soap stock

Acidulated corn oil soap stock parts 60
Isopropanol do 1.8 65
Ethylene dichloride:
1st portion do 30
2d portion do 50
Additional portions three 150-part portions
Potassium hydroxide (45% aqueous) parts 28.8
Water do 7.4

The acidulated soap stock, isopropanol and first portion of ethylene dichloride were blended

together in a kettle, an atmosphere of nitrogen being maintained over the surface of the kettle during this and all succeeding operations. The potassium hydroxide was then added and stirred in, the temperature rising to 40° C. from the heat of saponification. Stirring was discontinued, and the mass allowed to set for 18 hours. Thereafter, the mass was heated to 60° C., the second portion of ethylene dichloride added, and the mass stirred well for 5 minutes. The water was then added and the mass stirred for 15 minutes, maintaining the temperature throughout at 60° C. Thereafter, the stirring was discontinued, and the mass permitted to cool to 24° C. and allowed to stratify. The lower, ethylene dichloride extract, layer (hereinafter "Q") was drawn off. The residual soap stock was mixed with the third portion of ethylene dichloride, the mass heated to 60°, vigorously agitated, cooled to 24° C., permitted to stratify, and the lower, ethylene dichloride extract, layer ("R") drawn off. This procedure was repeated with the remaining portions of ethylene dichloride, and the resultant extracts combined with the extracts "Q" and "R." The combined extracts were filtered and subjected to vacuum distillation to remove the ethylene dichloride, leaving 2.61 parts of a brown, solid, highly effective, antioxidant product "S."

EXAMPLE XIV

Acetone extract of product "S"

	Parts
Products "S" (Example XIII)	778
Acetone	3112

35 The product "S" and acetone were mixed and heated to 50° C. to effect a clear solution. The mass was then cooled to -18° C. and filtered. The filtration residue was washed with a little acetone at -18° C., these washings being combined with the filtrate. The combined filtrate and washings were subjected to distillation to remove the acetone, leaving 34.8 parts of a product "T" having good antioxidant properties.

EXAMPLE XV

High vacuum distillation refinement

Product "T"	parts 100
Methanol	three 400-part portions

50 The product "T" was mixed with the first portion of the methanol, heated to 60° C., chilled to -18° C., and filtered. The filtration residue was then reextracted successively with the other two portions of methanol. All the filtrates were combined and the methanol evaporated off therefrom, leaving a dark maroon residue exhibiting strong antioxidant properties. This residue was then subjected to high vacuum distillation at 10⁻⁵. The fraction coming over at about 135° C. was a light yellow oil which was quite fluid at -10° C. and exerted outstanding antioxidant power. The non-volatile fraction also exhibited some antioxidant properties.

STABILITY TESTS

A number of the antioxidant products produced as described in the above examples were mixed with various oxidation labile products such as vitamin oils, feeds, cosmetic preparations, butter, salad oils, and the like in proportions of about 1 per cent of antioxidant on the base of the material to be stabilized and were found to markedly inhibit oxidative deterioration thereof. It was likewise found that when a small portion of a phosphatide such as cephalin, lecithin, soybean

lecithin, corn lecithin, or the like was added to the stabilized compositions along with the antioxidants of this invention, greatly enhanced protection was obtained. In order to evaluate the products of this invention quantitatively, the stability of a selected carbon-refined vitamin A-containing shark liver oil with and without the several antioxidants of this invention was checked by a series of tests each conducted as follows:

20 grams of the oil (or oil containing the antioxidant under test) were placed in a standard 100 ml. beaker and exposed to the atmosphere in an oven maintained at 34.5° C. The vitamin A potency of the oil or stabilized oil was noted both at the start of the test and after stated intervals, and the percentage of destruction of the vitamin A was calculated. The results are tabulated herewith, and it will be apparent that the antioxidants of this invention effectively restrain the destruction of vitamin A in compositions containing them. Likewise, it will be noted that in certain cases phosphatides were added and exerted a still further antioxidant effect, although the phosphatides in themselves exert only negligible antioxidant powers.

NOTE 1: A purified soyabean lecithin sold under the trade name "Yelkin."

NOTE 2: A commercial soyabean lecithin.

From the foregoing general discussion and specific examples, it will be apparent that this invention provides novel and highly effective antioxidants. It will also be seen that these antioxidants may be extracted by relatively simple and expeditious manipulations from relatively plentiful and cheap raw material sources, i. e. the soap stocks obtained as by-products in the refinement of vegetable oils.

The invention having been thus described, what is believed to be specifically novel, and is desired to be secured by Letters Patent, is:

1. Process for producing an antioxidant product from a soap stock obtained in the alkali re-

finement of a vegetable oil, which comprises contacting said soap stock with ethylene dichloride at a temperature between about 40° and about 90° C., whereby the ethylene dichloride forms a solution of antioxidant substances in the soap stock; separating the ethylene dichloride solution from the soap stock, and removing the ethylene dichloride from the solution to leave a residue containing said antioxidant substances.

10 2. Process for producing an antioxidant product from a soap stock obtained in the alkali refinement of a corn oil, which comprises contacting said soap stock with ethylene dichloride at a temperature between about 40° and about 90° C., whereby the ethylene dichloride forms a solution of antioxidant substances in the soap stock; separating the ethylene dichloride solution from the soap stock; and removing the ethylene dichloride from the solution to leave a residue containing said antioxidant substances.

15 3. Process for producing an antioxidant product from a soap stock obtained in the alkali refinement of a soybean oil, which comprises contacting said soap stock with ethylene dichloride at a temperature between about 40° C. and about 90° C., whereby the ethylene dichloride forms a solution of antioxidant substances in the soap stock; separating the ethylene dichloride solution from the soap stock; and removing the ethylene dichloride from the solution to leave a residue containing said antioxidant substances.

20 4. Process for producing an antioxidant product from a soap stock obtained in the alkali refinement of a cottonseed oil, which comprises contacting said soap stock with ethylene dichloride at a temperature between about 40° and about 90° C., whereby the ethylene dichloride forms a solution of antioxidant substances in the soap stock; separating the ethylene dichloride solution from the soap stock; and removing the ethylene dichloride from the solution to leave a residue containing said antioxidant substances.

25 5. Process for producing an antioxidant product from a soap stock obtained in the alkali refinement of a vegetable oil, which comprises contacting said soap stock with ethylene dichloride at a temperature between about 60° and about 70° C., whereby the ethylene dichloride forms a solution of antioxidant substances in the soap stock; separating the ethylene dichloride solution from the soap stock; and removing the ethylene dichloride from the solution to leave a residue containing said antioxidant substances.

30 6. An antioxidant composition produced from a soap stock obtained in the alkali refinement of a vegetable oil, said antioxidant composition being produced by contacting said soap stock with ethylene dichloride at a temperature between about 40° and about 90° C. whereby the ethylene dichloride forms a solution of antioxidant substances in the soap stock; separating the ethylene dichloride solution from the soap stock; and removing the ethylene dichloride from the solution to leave a residue containing said antioxidant substances.

35 7. An antioxidant composition produced from a soap stock obtained in the alkali refinement of a corn oil, said antioxidant composition being produced by contacting said soap stock with ethylene dichloride at a temperature between about 40° and about 90° C., whereby the ethylene dichloride forms a solution of antioxidant substances in the soap stock; separating the ethylene dichloride solution from the soap stock; and removing the ethylene dichloride from the solution to leave a residue containing said antioxidant substances.

40 8. An antioxidant composition produced from a soap stock obtained in the alkali refinement of a soybean oil, said antioxidant composition being produced by contacting said soap stock with ethylene dichloride at a temperature between about 40° C. and about 90° C., whereby the ethylene dichloride forms a solution of antioxidant substances in the soap stock; separating the ethylene dichloride solution from the soap stock; and removing the ethylene dichloride from the solution to leave a residue containing said antioxidant substances.

45 9. An antioxidant composition produced from a soap stock obtained in the alkali refinement of a cottonseed oil, said antioxidant composition being produced by contacting said soap stock with ethylene dichloride at a temperature between about 40° and about 90° C., whereby the ethylene dichloride forms a solution of antioxidant substances in the soap stock; separating the ethylene dichloride solution from the soap stock; and removing the ethylene dichloride from the solution to leave a residue containing said antioxidant substances.

50 10. An antioxidant composition produced from a soap stock obtained in the alkali refinement of a vegetable oil, said antioxidant composition being produced by contacting said soap stock with ethylene dichloride at a temperature between about 60° and about 70° C., whereby the ethylene dichloride forms a solution of antioxidant substances in the soap stock; separating the ethylene dichloride solution from the soap stock; and removing the ethylene dichloride from the solution to leave a residue containing said antioxidant substances.

55 11. An antioxidant composition produced from a soap stock obtained in the alkali refinement of a corn oil, said antioxidant composition being produced by contacting said soap stock with ethylene dichloride at a temperature between about 40° and about 90° C. whereby the ethylene dichloride forms a solution of antioxidant substances in the soap stock; separating the ethylene dichloride solution from the soap stock; and removing the ethylene dichloride from the solution to leave a residue containing said antioxidant substances.

60 12. An antioxidant composition produced from a soap stock obtained in the alkali refinement of a soybean oil, said antioxidant composition being produced by contacting said soap stock with ethylene dichloride at a temperature between about 40° C. and about 90° C., whereby the ethylene dichloride forms a solution of antioxidant substances in the soap stock; separating the ethylene dichloride solution from the soap stock; and removing the ethylene dichloride from the solution to leave a residue containing said antioxidant substances.

65 13. An antioxidant composition produced from a soap stock obtained in the alkali refinement of a cottonseed oil, said antioxidant composition being produced by contacting said soap stock with ethylene dichloride at a temperature between about 40° and about 90° C., whereby the ethylene dichloride forms a solution of antioxidant substances in the soap stock; separating the ethylene dichloride solution from the soap stock; and removing the ethylene dichloride from the solution to leave a residue containing said antioxidant substances.

70 14. An antioxidant composition produced from a soap stock obtained in the alkali refinement of a vegetable oil, said antioxidant composition being produced by contacting said soap stock with ethylene dichloride at a temperature between about 60° and about 70° C., whereby the ethylene dichloride forms a solution of antioxidant substances in the soap stock; separating the ethylene dichloride solution from the soap stock; and removing the ethylene dichloride from the solution to leave a residue containing said antioxidant substances.

75 15. An antioxidant composition produced from a soap stock obtained in the alkali refinement of a corn oil, said antioxidant composition being produced by contacting said soap stock with ethylene dichloride at a temperature between about 40° and about 90° C., whereby the ethylene dichloride forms a solution of antioxidant substances in the soap stock; separating the ethylene dichloride solution from the soap stock; and removing the ethylene dichloride from the solution to leave a residue containing said antioxidant substances.

13

ganic solvent to remove inactive materials; and subjecting the residue to high vacuum distillation to recover a fraction of increased antioxidant potency.

LORAN O. BUXTON.
